CLAIM

The ornamental design for a rotating storage rack, as shown and described.

DESCRIPTION

FIG. 1 is a front, right, top perspective view of a rotating storage rack, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a sectional view of 9-9 along the line in FIG. 3. The dashed broken lines in the figures are for the purposes of illustrating portions of the rotating storage rack and form no part of the claimed design.

The area between the thick solid line and the dashed broken line in the figure is not protected.
